DISCHARGE DEVICE

Nelson H. Stewart, Verona, N. J., assignor to
Westinghouse Lamp Company, a corporation of
Pennsylvania

Application September 30, 1933, Serial No. 691,575

1 Claim. (Cl. 250—35)

This invention relates to electric discharge devices and more particularly to devices of this character employed in the X-ray field and commonly termed X-ray tubes. In its more specific aspect the invention is directed to an improved construction in X-ray tubes of the type disclosed in the United States patent to Nelson H. Stewart, which patent was issued on August 1, 1933 and bears the number 1,920,606.

Said patent discloses an X-ray tube comprising an elongated envelope having an anode, a cathode and an X-ray screening means therein. The screen houses the target end of the anode and the cathode to screen out undesirable X-rays. The screen is composed of nickel-iron and is relatively heavy. Because of the weight of the screen it has been necessary to provide means for supporting the same within the tube. Heretofore, for this purpose, it has been proposed to employ a plurality of plates and conducting wires. The conducting wires served to aid in the supporting of the screen as well as providing a conducting path for the current to be supplied to the cathode. These wires were sealed directly in said envelope, forming a glass-to-metal wire seal and extended exteriorly and interiorly of said envelope. The interior portions of said wires were mechanically connected to said screen and electrically connected to the cathode.

The screen, solely supported by said wires, was not a commercially feasible construction because the entire weight of the screen is carried by the seals. In normal transportation and when subjected to the shocks incident to manipulation and operation, the seals sometimes fractured because the glass was strained at the seals. In order to prevent said screen from striking the side wall of the envelope there are provided a plurality of resilient plates located between the screen and envelope. So that the screen might not be totally supported by said seals and by the frictional engagement of said screen and envelope with the resilient plates, at least one of the plates has an upstanding ear with an opening therein through which projects a nipple on the interior of said envelope. The resilient plate, whose ear surrounds said nipple, supports said plate to maintain the screen from sliding longitudinally in said tube.

Although the aforesaid arrangement has served the purpose of supporting the screen, tubes of this construction have not always been satisfactory for other reasons and, in addition, manufacturing difficulties were encountered in production. Generally, the nipple is formed by merely heating the evacuated bulb, containing the internal parts, at a restricted area just opposite the opening in the ear of the resilient plate. In some cases the glass is heated too

highly at this area or, for some other reason, the heated glass is drawn in and bubbles so that it is readily pierced. Even when the nipple is properly formed, that portion of the glass which has been heated has its internal structure changed. As a consequence it is strained at that point and may crack upon cooling or in normal manipulation, transportation or operation. Of course annealing the glass after the nipple is formed suggests itself as a solution, but it is not commercially feasible because it is too difficult to carry out when the nipple has a vacuum on one side.

In order to eliminate these physical shortcomings inherent in the tubes heretofore manufactured, I have developed the following invention. Briefly stated, the invention comprises the elimination of a wire-to-glass seal to support the screen and also the elimination of the vitreous teat or nipple for supporting the screen. For this purpose, I employ one or more copper thimbles ring-sealed to the envelope and connected to said screen for supporting the same.

An object of my invention is to provide an electric discharge device whose heavy elements are supported by a ring seal to render them more rugged and so that shrinkage during manufacturing is considerably reduced.

Another object of my invention is to provide an electric discharge device containing no glass-to-wire seals, but only ring seals.

Another object of my invention is to provide an X-ray tube that is more rugged than those heretofore produced.

A still further object of my invention is to provide an X-ray tube whose heavy screen is supported by a ring seal.

These and other objects of my invention may be readily ascertained from the following specification and drawing wherein,

Figure 1 represents a longitudinal cross sectional view with some of the parts in elevation of an X-ray tube embodying my invention;

Figure 2 represents a fragmentary view illustrating a modification of the supporting means shown in Figure 1; and

Figure 3 represents a perspective view of the thimble that I employ in my invention as shown in Figures 1 and 2.

As shown in Figure 1 the X-ray tube comprises a highly evacuated vitreous envelope 10 having a body portion 11 of generally cylindrical form with a hemispherical portion 12 at one end and a reentrant tube 13 at its other end. This reentrant tube 13 extends upwardly into the body portion, and has a copper sleeve or support coupling 14 hermetically sealed thereto. An anode extension 15 is secured to and carried by said coupling 14. An anode 16 is located within the envelope and is also carried by

said support coupling 14. Intermediate the lower end of the anode 16 and the coupling 14 is a thimble shield 17 whose lower end extends below the seal between the coupling 14 and the 5 reentrant tube 13.

Fusedly ring-sealed to the inner wall of the envelope 10 is a vitreous tubular cylinder 18 extending upwardly in the envelope. The anode 16 is surrounded by said cylinder or sleeve 10 18. A plurality of resilient plates 19 bear against the outer surface of the anode and the inner surface of the sleeve 18 to partially support the anode and to absorb mechanical shocks.

Disposed around and having its interior wall 15 spaced from the free end of the anode 16 is an X-ray screen composed of nickel-iron and consisting of a cylindrical portion 20 and a top plate 22 secured to each other in any convenient manner. The X-ray screen houses the 20 free end of the anode and a cathode 23 together with its focusing cup 24.

According to my invention I provide a novel means for supporting said screen, which means may also serve as the conductors of electricity 25 for the cathode 23. My novel means comprises essentially the employment of a cap or thimble having its free circular edge ring-sealed by fusion to a small cylindrical section extending from the wall of the envelope. This type of construction 30 permits the construction of more rugged X-ray tubes and also lowers the manufacturing costs because it reduces the percentage of tubes whose envelopes had to be discarded and the parts reassembled when the old type of support 35 was employed.

In carrying out my invention, the upper end 40 of the cylindrical portion 11 of the envelope has a pair of diametrically disposed short outwardly extending small cylindrical vitreous sleeves 25 and 26. United to the outer ends of said sleeves 25 and 26 by fusion are, respectively, short re-entrant vitreous tubular sleeves 27 and 28. The free ends of these sleeves 27 and 28 are spaced 45 a slight distance from the inner walls of the sleeves 25 and 26. A thimble or cap 29 composed of copper or the like is secured to each of said sleeves 27 and 28 and to the X-ray screen to properly support the latter.

As illustrated, the thimbles or caps 29 may 50 be of any desired shape. The rims of the caps or thimbles 29 are tapered downwardly towards the free edges. The caps 29 are secured to the short tubular sleeves 27 and 28 by a simple fusion process so that the joint between the glass and metal shall be a hermetic and air-tight seal. Integrally united to the base of the caps 55 29 are conducting rods 30 and 31 which may be of the same composition as the cap per se. The rods 30 extend outwardly from said caps and the rods 31 60 are located within said envelope.

A cap, having rods 30 and 31, may be machined out of a single piece of metal. The outer or free ends of the rods 31 are threaded. Inverted J-shaped rigid supports 33 and 34 are secured onto 65 the inner rods 31. The outer portion of the elongated arms of the members 33 and 34 are also screw threaded. The screw threaded portion of the rod 34 is threadedly secured to a threaded opening 35 in the top plate of the X-ray screen member.

An opening diametrically disposed with relation to the opening 35 has an insulating bushing 36 located therein. Passing through said bushing 75 which insulates the same from the X-ray

screen member is the threaded portion of the rod 33. A nut 37 is screwed onto each of the outermost ends of the rods 33 and 34. The outer ends of the cathode 23 are secured to the outer ends of the rods 33 and 34. Thus the rods 33 and 34 act as supports for both the screen member and the cathode. 5

In order that the entire weight of the X-ray screen member need not be carried by the caps 29 and also in order that the tube shall be further 10 protected from mechanical shocks, I provide a plurality of spaced resilient plates 39. These plates 39 are of the type disclosed by A. C. Blakeman in his copending application Serial No. 560,738 filed September 2, 1931 and assigned to 15 the same assignee as the present invention. The plates 39 are spaced around the screen and bear against the outer surface of the screen and the inner wall of the envelope. With my construction and especially because I use the thimbles or 20 caps 29, I need not employ a resilient plate having an upstanding ear with an opening therein fitting around a vitreous nipple in the envelope. As a matter of fact with the construction shown in Figure 1, it is not necessary that I employ a 25 resilient plate having an upstanding ear.

However, it is within the purview of my invention to employ a resilient plate having an upstanding ear. Sometimes I may desire to substitute a flexible member for the members 33 and 34. When this is a prerequisite or desirable, I 30 employ a structure such as shown in Figure 2. For the members 33 and 34 shown in Figure 1, I 35 may substitute flexible members such as 40, secured respectively to the rods 30 and 31 and associated with the screen in the same manner as the rods 33 and 34. One of the resilient plates 39 may have an ear 42 with its opening fitting over the rod 31 to prevent excess longitudinal displacement of said screen. If I desire, I may 40 have an ear on each of two resilient plates, with the openings in said ears fitting respectively over the rods 30 and 31 and mounted on an insulator 43, as shown. Contact caps 44 fit over the outwardly extending vitreous sleeves and are sealed 45 with a basing cement 45 and soldered to the outwardly extending rods 30.

Although I have described my invention with 50 some particularity it is not to be limited to the exact construction shown and described, but only by the prior art.

What is claimed is:

An X-ray tube comprising an elongated vitreous envelope, an anode, a cathode and an X-ray 55 screen therein, said envelope consisting of a body portion, a reentrant tube in the lower end of said body portion, a hemispherical portion at the upper end of said body portion, a pair of diametrically opposed vitreous tubular sections integral 60 with said body portion and extending therefrom, a short reentrant vitreous tube integral with each section, a plurality of metallic caps carried by said reentrant tubes, each of said reentrant tubes having one of said caps ring-sealed thereto, said 65 anode electrically connected to one of said caps, a cathode electrically connected to said other caps, means connected to said screen and one of said caps for supporting said screen, and a plurality of resilient plates bearing against the outer surface of said screen and the inner surface of said envelope to also support said screen and protect the envelope from mechanical shocks. 70
